MORRIS KATCHER, OF BROOKLYN, AND HARRY BRUDNEY, OF NEW YORK, N. Y.

DIE-CASTING MACHINE.

Application filed August 26, 1922. Serial No. 584,506.

Our invention relates to die-casting machines having a movable ladle or carrier device in addition to a melting pot, irrespective of whether the die is operated by hand or power mechanism, and to machines, irrespective of how the metal is poured, in which the die is power operated.

In the present type of die-casting machines which use a ladle that is caused to dip into a pot of molten metal, then to deliver this metal under pressure into a die by being lifted from the pot and moved into contact with the die opening, the entire weight of the ladle and its contents must be lifted by the operator. An object of this invention is so to counterbalance the weight of the ladle that the exertion on the part of the operator is reduced to a minimum. Another object of this invention is the provision of means which prevent the tilting of the ladle on its way from the melting pot to the die, thereby insuring the carrying of a maximum charge of metal.

Heretofore in die-casting machines in which the ladle is moved bodily from the melting pot over to the die, the ladle was always kept connected to the compressed air supply either by a flexible coupling or by articulated tubing. This air connection has been a constant source of trouble, either by deteriorating or becoming clogged. In the present invention, the air connection has been entirely eliminated. We use a ladle which is completely disconnected from the pressure source when it is dipped into the melting pot. Our ladle is provided merely with an air inlet or opening which can be brought over into registration with the pressure source at the time when it is desired to eject the metal from the ladle into the die. Our ladle which is normally open to the atmosphere at both ends, is dipped into the melting pot. When it has received its charge, the ladle is moved up into registration at one end with the compressed air supply and at its other end with the opening of the die. The air supply is provided with an opening which is adjustable both horizontally and vertically. Also the ladle is so mounted that it can be adjusted horizontally and vertically. These adjustments permit the use of a die which has considerable leeway in the location of its

gate. A great advantage results from this feature in that it permits the location of the gate in the die where it is most suitable, instead of requiring the gate to be in practically one fixed position as is necessary in the machines of the prior art. Another feature of our construction is the elimination of the comparatively long passage between the mouth of the ladle and the opening in the die as in prior machines. The mouth of our ladle is brought directly against the opening in the die.

Another object of this invention is to provide a construction in which the levers are all grouped on one side of the machine, making it convenient to be operated by one man.

Our die is operated by a positive mechanical drive instead of fluid pressure as in many of the previous machines. We use a type of automatic clutch that has been long in successful use in the mechanical arts, a clutch such as is customarily used in power presses. One motion of the lever connects the power from the flywheel to close the die. When the die has reached its closed position, the die moving mechanism is automatically disconnected from the power source. Another motion of the lever and the die is opened, the power also being automatically cut off when the die has reached its open position.

In die-casting it is desirable to keep the molten metal at a predetermined constant temperature. Heretofore in order to accomplish this a pyrometer has been used which it was customary to insert directly into the molten metal in the melting pot. Certain metals, especially molten aluminum, badly deteriorate the metallic parts of the pyrometer with which they come in contact. In order to obviate this, we have provided a pocket in the melting pot in which pocket lead or another substance not harmful to the pyrometer is kept. The pyrometer is dipped into the metal of this pocket out of contact with the harmful metal adjacent in the main body of the pot, enabling it to indicate the temperature and still be not subject to deterioration.

Other objects and advantages will become apparent upon further reading of this specification and a study of the drawings.

In the accompanying drawings wherein is

illustrated one embodiment of the invention, Fig. 1 is a side elevation of the machine, Fig. 2 is a plan view, Fig. 3 is a front elevation with the furnace and melting pot removed and Fig. 4 is a rear end elevation.

The melting pot 5 is set in furnace 6 which can be of any suitable type such as is well known in the art of die-casting. In melting pot 5 is located a well 7 adapted to be filled with molten lead while the main cavity of pot 5 is filled with the metal to be cast. The pyrometer (not shown) is inserted in well 7 where its contact with the molten lead indicates the temperature of the adjacent metal in the pot. As explained above the use of a separate lead well is to prevent the deterioration of the metallic parts of the pyrometer which are attacked when in contact with certain molten metals as aluminum. The ladle or carrier device 8 is formed with a goose neck at one end in which is inserted a removable bushing or nozzle 9. The advantage of having a removable nozzle, such as 9 is that it is in this location where rapid deterioration takes place. Instead of having to provide a new ladle 8 when worn at its mouth, a new nozzle 9 can be supplied. The ladle 8 is formed of two main portions, an upper and lower portion fastened together by screws 10. The lower portion of the ladle 8 which is subjected to the action of the hot metal is destroyed more rapidly than the upper portion and our construction permits the renewal of the lower portion when worn without having to replace the whole ladle. Of course it is to be understood that a ladle made of one piece also could be used in our machine excepting that the advantage just noted would be lost.

The upper portion of ladle 8 which is hollow, is fitted at its end with an adjustable nipple 11. A rib 12 (Fig. 1) is formed on the upper portion of ladle 8 which carries bosses 13 (Figs. 2 and 3). The ladle 8 is swingingly mounted on trunnion shaft 14 which passes through bosses 13 and rib 12. Adjustable collars 15 are fastened on shaft 14 adjacent to bosses 13. By shifting collars 15 on shaft 14, a lateral adjustment of ladle 8 can be had. The ends of shaft 14 fit into boxes 16 which are adjustably mounted in rectangular frames 17 formed on the tops of arms 18. The vertical adjustment of shaft 14 and hence of ladle 8 is accomplished by means of set screws 19 which retain boxes 16 in place in frames 17.

Normally ladle 8 which is hung on shaft 14 would tend to swing in a counterclockwise direction from that shown in Fig. 1. This swinging is prevented and the mouth of the ladle kept substantially horizontal by the bearing of roller 20, which is carried by rib 12, against the underside of the stationary cam 21. Cam 21 is so formed that ladle 8

is kept substantially vertical throughout its motion from the melting pot to the die.

The lower ends of arms 18 are fixedly mounted on shaft 22 which is in turn mounted in suitable bearings in frame 23 of the machine.

Crank lever 24 is mounted and fixed to shaft 22 immediately next to the right hand arm 18 (Fig. 3). A roll 25 is mounted on a stud 26 carried by crank lever 24. Another crank lever 27 is carried by shaft 22 adjacent to the left hand arm 18. Crank lever 27 has mounted on it a roller 28. Shaft 22 also carries a counterweight lever 29 best seen in Fig. 1. Adjustably mounted on counterweight lever 29 is the counterweight 30. Counterweight lever 29 and counterweight 30 are provided to counterbalance the weight of ladle 8.

In close proximity to shaft 22 is mounted in suitable bearings in frame 23, shaft 31. Fixed to shaft 31 opposite crank lever 24 is lifting cam 32. Lever 33 is fixed to shaft 31 adjacent to lifting cam 32. On the other end of shaft 31 is fixed lowering cam 34. Fig. 1 shows lever 33 in its lowest position with lifting cam 32 pressed and locked against roller 25, holding ladle 8 in its upper position, with its nozzle 9 in register with the opening of die 35 and its nipple 11 in contact with the compressed air nozzle 36. It is important that ladle 8 be pressed against these openings with sufficient force to resist the action of the air pressure when it is introduced into ladle 8 to force out the metal into the die. In order to insure this, the bearings of stud 26 in the forked arms of lever 24 are formed eccentric with the portion of said stud on which is mounted roller 25 (Fig. 1). By turning the head 37 (Fig. 3) formed on the end of stud 26, roller 25 can be brought nearer, or farther away from cam 32, thus accomplishing the adjustment of the pressure of ladle 8 against the opening into the die 35 and air nozzle 36. When lever 33 is lifted, cam 32 is released from roller 25. Further lifting of lever 33 brings cam 34 in contact with roller 28 and lowers ladle 8 into the melting pot 5 as shown by the dotted lines in Fig. 1.

Valve 38 which is connected to the compressed air supply (not shown) by means of pipe 39 is of a construction well known to the art and hence requiring no detailed description. When lever 40 is pulled down, compressed air is admitted to ladle 8. When lever 40 is released, spring 41 returns it to its upper position shutting off the compressed air supply and opening up the interior of the ladle to the atmosphere through an exhaust port in valve 38.

In order to insure proper registration of nipple 11 of ladle 8 with the compressed air supply, nozzle 36 is mounted in plate 42 which can be adjusted to various positions.

Plate 42 is held in position by screws 43 (Figs. 2 and 3), horizontal slots 43 in plate 42 permitting of lateral adjustment. For vertical adjustment T slots 45, into which the heads of screws 43 fit, are provided in bracket 46 of the frame.

The die consists of two main parts, the fixed portion 35 which is fastened to the front frame 23 of the machine and the movable portion 47 which is fastened to plate 48. Plate 48 is provided with four sleeves 49 which are adapted to slide on four corresponding guide rods 50. The guide rods are held at their front ends in frame 23 and at 15 their rear in frame 51.

From the rear of plate 48 extends a bracket 52, through a hole in which wrist pin 53 fits. Wrist pin 53 also fits in forked connecting member 54. Pitman 55 is screwed at 20 its forward end into connecting member 54 while at its rear end it is screwed into a connecting member 56 which is provided with a bearing for crank pin 57. The ends of pitman 55 are oppositely threaded and provided 25 with lock nuts 58. This permits of adjusting the distance between wrist pin 53 and crank pin 57 to suit varying thicknesses of the die parts 35 and 47.

Crank pin 57 is carried by crank disc 59 which is fixedly mounted on shaft 60. On the other end of shaft 60 is fixedly mounted gear 61. Gear 62, which is fixed on shaft 63, meshes with gear 61.

The automatic pin clutch which is about 35 to be described is one which is well known to the arts, being often found on power presses, where the throwing in of a lever brings about one operation of the press.

The automatic pin clutch used in our machine consists as is usual of two parts, one part 64 which is fixed on shaft 63 carrying a spring actuated bolt 65, and the other part 66 which is loose on shaft 63 carrying pin 67. The clutch part 66 is formed integral 45 with gear 68 also loose on shaft 63.

Pulley wheel 69 adapted for belt drive is fixedly mounted on shaft 71. Pinion 70 which is also fixedly mounted on shaft 71 meshes with gear 68.

Lever 72 is fixed to the end of shaft 75 which carries fixed at its other end the irregular shaped lever 73. A lip on lever 73 is adapted to engage the lower end of a spring actuated pawl 74. Normally pawl 74 is held by its spring 76 in engagement with one of the two notches formed in the periphery of crank disc 59 locking said disc against rotation. Another lip on lever 73 is provided with a slot which is adapted to slide over pin 77 carried by pawl 78. Pawl 78 is pivoted at one end on pin 79. When pawl 78 is in the position shown in Fig. 1, it is adapted to hold bolt 65 out of engagement with pin 67 (Figs. 1 and 4) which is 55 in constant rotation, being driven by the

pulley 69 through shaft 71 and gears 70 and 68.

When lever 72 is lifted from the position shown in Fig. 1, lever 73 is first caused to disengage pawl 74 from the notch in crank 70 disc 59, the slot in lever 73 allowing it to rotate for a distance before it comes against pin 77. Further rotation causes lever 73 to depress pin 77 separating pawl 78 from spring actuated bolt 65. When bolt 65 is released, it shoots out into the way of the rotating pin 67. When pin 67 comes into engagement with bolt 65, clutch part 64 and gears 62 and 61 are rotated causing crank disc 59 to rotate. The operator will have 80 by this time dropped lever 72 bringing pawl 78 up into its original position. Now when bolt 65 reaches pawl 78 it is pulled out from engagement with pin 67 thereby disconnecting the power drive. The dropping of lever 85 72 also released pawl 74 so that it springs in against crank disc 59 stopping said disc at the next notch. It is thus seen that actuating lever 72 causes the power drive to turn crank disc 59 a half revolution while the 90 clutch part 64 is given a complete revolution, gears 62 and 61 having the gear ratio of one to two.

When crank pin 57 is in the position shown in Fig. 1, the movable die part 48 is locked 95 against its stationary mate 35, because pin 57 is at dead center and pawl 74 is in the notch in crank disc 59. This locking action is necessary to resist the pressure of the metal being forced into the die.

The operation of the machine is as follows: At the start of the cycle of operations, the die parts 35 and 47 are separated and ladle 8 is in the pot as shown in dotted position. The operator now lifts and releases lever 72, which causes the power drive, acting through the automatic clutch 64 and 66 and gears 62 and 61, to give crank disc 59 a half revolution, moving thereby the die part 47 to its mate 35. The operator now pulls down on lever 33 bringing up ladle 8 into registration with the opening in the die part 35 and with nozzle 36 of the compressed air supply. By pressing down hard enough on lever 33, ladle 8 is locked into this position due to the shape of lifting cam 32. The operator next pulls down on lever 40 which admits compressed air or any other suitable fluid into the top of the ladle 8 forcing out a part of the molten metal contained therein between the die parts 35 and 47. Lever 40 is then released, spring 41 pulling it upward. This cuts off the compressed air supply and opens the top of the ladle 8 to atmosphere through an exhaust port (not shown) in valve 38. The operator then lifts and releases lever 72 which causes the die to open. The machine is now ready for the next casting operation.

We wish it to be understood that our ladle and its operating means will work equally 130

well in a machine in which the opening and closing of the die is effected by hand as in many machines in use at the present time.

We claim:—

5. 1. In casting apparatus, the combination of a molten metal container, a source of fluid pressure, a die having a gate opening, a carrier device formed with a hollow interior, an opening in said carrier from 10 its interior adapted to serve as a mouth for the reception and discharge of the molten metal and another opening in said carrier from its interior adapted to serve as a fluid pressure inlet, said carrier being suitably 15 mounted and formed to permit the submergence of its mouth in the molten metal and the removal of its fluid pressure inlet from the source of fluid pressure in one position and in another position to permit the simultaneous registration of its mouth with said gate opening and its other opening with the source of fluid pressure and means independent of the die for effecting said changes of position of the carrier.
- 20 2. A casting machine having, in combination, a receptacle for the material to be cast, a die, a source of fluid pressure, a movable ladle for carrying the material to be cast from said receptacle to the die, said 25 ladle being adapted to permit its removal from the source of fluid pressure and to permit such material to flow into it when dipped into same, and means independent of the die; for moving said ladle into contact with the die and the source of fluid pressure, whereby when said fluid is admitted under pressure into said ladle, the material within it will be ejected into the die.
- 30 3. In casting apparatus, the combination of a molten metal container, a source of fluid pressure, a die having an opening therein, a carrier device having a hollow interior open at each end to the atmosphere, one end of said carrier serving as a mouth, 35 means independent of the die; for moving said carrier such that its mouth is dipped into said metal in one position, and in another position such that its mouth will be in registration with the die opening and 40 its other opening in registration with the source of fluid pressure.
- 45 4. In a device of the character described, the combination of a molten metal container, a die, a ladle supported over said container on a pivot, said pivot, means for bodily moving said pivot for raising and lowering said ladle in respect to the container and for laterally moving said ladle in respect to the die, a cam guide in operative relation to 50 said ladle, suitably formed to permit the ladle to have a motion only of substantially translation as it travels between its position in said container and its position of registration with the die.
- 55 5. A casting machine having, in combination, a molten metal container, a die, a source of fluid pressure, a ladle adapted to receive the metal from said container, means for controlling the supply of fluid pressure to said ladle, means independent of the die, 60 for causing separation between said ladle and said source of fluid pressure and between said ladle and said die, and for causing contact between said ladle and said source of fluid pressure and between said ladle and 65 said die, whereby when said fluid is admitted under pressure into the ladle, the material within it will be ejected into the die.
- 70 6. In casting apparatus, the combination of a molten metal container, a ladle, a trunnion shaft upon which said ladle is mounted, arms supporting said shaft for raising and lowering it and the ladle in respect to the molten metal container, a second shaft upon which said arms are fixedly mounted, a 75 lever fixed to said second shaft, a pivotally mounted operating lever, a cam lever adapted to be rotated by said operating lever and of suitable form to rotate the lever fixed to said second shaft and lock with it whereby the trunnion shaft can be raised and locked in its raised position.
- 80 7. In casting apparatus, the combination of a molten metal container, a die, a ladle suitably mounted to be raised and lowered 85 bodily in respect to said container and die for transferring the molten metal from the container to the die, means for bodily raising and lowering said ladle, means for counterbalancing the weight of said ladle adapted to cooperate with the means for moving the ladle and means for locking the ladle both in its raised and lowered positions.
- 90 8. In casting apparatus, the combination of a molten metal container, a ladle, means for supporting said ladle and for raising and lowering it and moving it laterally in respect to said container, a shaft upon which said supporting means are fixedly mounted, a suitably weighted lever fixed to said shaft 95 for counterbalancing the weight of said ladle, and means for rotating said shaft.
- 100 9. In casting apparatus, the combination of a molten metal container, a source of fluid pressure, a nozzle for said source adjustable both in a horizontal and vertical direction, a die having an opening, a carrier device having a hollow interior normally open at each end to the atmosphere, one end of said container serving as a mouth, 105 means for moving said carrier such that its mouth is dipped into said metal in one position, and in another position such that its mouth will be in registration with the die opening while its other opening is in registration with said nozzle, the adjustability of said nozzle being provided to permit registration with same of that end of the carrier adapted for registration with the nozzle, 110 when the position of said mouth for regis-
- 115 120 125 130

tration with the die opening, must be shifted to suit variations in the location of the die opening.

10. In casting apparatus, the combination of a molten metal container, a source of fluid pressure, a die having an opening, a carrier device having a hollow interior normally open at each end to the atmosphere, one end of said carrier serving as a mouth, means for moving said carrier such that its mouth is dipped into said metal in one position and in another position such that its mouth will be in registration with the die opening and its other opening in registration with the source of fluid pressure, and adjustable means intervening between said moving means and the carrier device adapting said carrier device to allow for both vertical and horizontal variation in the location of the die opening.

11. In casting apparatus, the combination of a molten metal container, a source of fluid pressure, a stationary nozzle for said source, a die having an opening, a carrier device having a hollow interior normally open to the atmosphere at each end, one end of said carrier serving as a mouth, means for moving said carrier such that its mouth is dipped into said metal in one position and in another position such that its mouth will be in registration with the die opening and its other opening in registration with said nozzle, said carrier device being adjustably mounted on its moving means and said nozzle also being adjustably locatable to allow for variation in the location of the die opening.

12. A casting machine having, in combination, a receptacle for the material to be cast, a die having an opening therein, a source of fluid pressure, a ladle supported over said receptacle on a pivot, said pivot, means for bodily moving said pivot for lowering and raising said ladle in respect to said receptacle, die and source of fluid pressure, said ladle being adapted to permit said material to flow into it when dipped into same and to permit its registration both with the die opening and the source of fluid pressure when raised, and means for permitting the adjustment of said ladle laterally on said pivot to allow for any variation in the location of the die opening.

13. A casting machine having, in combination, a receptacle for the material to be cast, a die having an opening therein, a source of fluid pressure, a ladle supported over said receptacle on a pivot, said pivot, means for bodily moving said pivot for lowering and raising said ladle in respect to said receptacle, die and source of fluid pressure, said ladle being adapted to permit said material to flow into it when dipped into same and to permit its registration both with the die opening and the source of fluid

pressure when raised, and means for adjusting the location of said pivot on the means for moving it to allow for any variation in the location of the die opening.

14. In casting apparatus, the combination of a molten metal container, a source of fluid pressure, a die having an opening therein, a ladle having a hollow interior normally open at each end to the atmosphere, one end of said ladle serving as a mouth, an adjustably extensible nipple mounted at the other end, means for moving said carrier such that its mouth is dipped into said metal in one position, and in another position such that its mouth will be in registration with the die opening and said nipple in registration with the source of fluid pressure.

15. In casting apparatus, the combination of a molten metal container, a die having a fixed and a movable part, means for delivering the metal from said container to said die under pressure, a source of rotational power, means for moving the movable die part, means for connecting the source of power to said die moving means for either closing said die or for opening said die, and means adapted automatically to disconnect said power source from said die moving means both when said die arrives at its open and its closed positions.

16. In die-casting apparatus, a die having a fixed and a movable part, a source of power, means for moving the movable part, means for connecting the source of power to said die moving means for either closing said die or for opening said die, and means for automatically disconnecting said power source from said die moving means both when said die arrives at its open and its closed positions.

17. In die-casting apparatus, a die having a fixed and a movable part, means for moving the movable die part, a rotating flywheel for supplying power, a clutch adapted to connect the driving power of the flywheel with said die moving means through suitable gearing, said gearing adapted to have one revolution of the clutch cause the die to be opened and another revolution of the clutch to cause the die to be closed and means for automatically disengaging said clutch both when said die substantially reaches its open and its closed positions.

18. In die-casting apparatus, a die having a fixed and a movable part, means for moving the movable die part, a source of rotational power, means for connecting the source of power with said die moving means, a lever adapted when tripped either to actuate the connecting means to connect the source of power with the die moving means to open the die and to disconnect said power source automatically from said die moving means when said die has substantially ar-

rived at its open position, or to actuate the connecting means to connect the source of power with the die moving means to close the die and to disconnect said power source automatically from said die moving means when said die has substantially arrived at its closed position.

19. In a die-casting apparatus, a die having a fixed and a movable part, means for 10 moving the movable die part, a source of power, means for connecting the source of power to said die moving means either for opening or closing said die, means adapted to disconnect said power source from said 15 die moving means automatically both when said die is in substantially open and closed positions, and means for positively stopping said movable die part automatically both in its open and closed positions.

20. In a die-casting apparatus, a die having a fixed and a movable part, means for moving the movable die part, a source of power, means for connecting the source of power to said die moving means either for 25 opening or closing said die, means adapted to disconnect said power source from said die moving means automatically both when said die has substantially arrived at its open and closed positions and means for positively stopping said movable die part automatically when it has reached its closed position.

21. In a device of the character described, the combination of a molten metal container, a die, a source of fluid pressure, a ladle adapted to be in simultaneous registration with said source and the die and to be lowered into said container to receive its charge of metal, and means suitably constructed for 35 moving the ladle out of contact with said source and the die and lowering said ladle into the container and then raising the ladle out of said container and bringing it over laterally into registration with said source 40 and the die, said means being adapted to cause the ladle to have a motion of translation substantially throughout its travel.

22. In a device of the character described, the combination of a molten metal container, a die, a ladle, and means for lowering said ladle into the container to receive its charge of metal and then raising said ladle and bringing it over laterally into registration with said die, said means being 50 adapted to cause the ladle to have a motion of translation substantially throughout its travel.

23. In casting apparatus, a melting pot for holding molten metal to be cast, said 55 melting pot containing a well within it without openings between the interior of said well and the interior of said pot, being adapted thereby to hold molten metal dissimilar to that to be cast, said well 60 being adapted to hold a pyrometer in it

and being suitably located within said pot so that it is immersed in the metal to be cast.

24. In casting apparatus, a melting pot for holding molten metal to be cast, having an independent well situated within it for 70 holding molten metal dissimilar to that to be cast, said well being adapted to hold a pyrometer in it and being adapted to be in contact with the metal to be cast.

25. In casting apparatus, a melting pot, 75 for holding molten metal to be cast, having an independent well situated within it, said well being adapted to hold a pyrometer and being adapted to be in contact with the metal to be cast, and metal, located within said 80 well, adapted to leave the metallic parts of a pyrometer placed in it, unaffected.

26. In a die-casting apparatus, in combination, a receptacle for the material to be cast, a source of fluid pressure, a die, a 85 movable ladle for carrying the material to be cast from said receptacle to the die, said ladle being formed of two main separable parts, one of which parts being adapted to have contact with the material to be cast 90 and the other of said parts being adapted to be connected to the source of fluid pressure, whereby when either of said parts has become deteriorated it can be replaced independently of the other part.

27. A casting machine having, in combination, a receptacle for the material to be cast, a die, a source of fluid pressure, a movable ladle for carrying the material to be cast from said receptacle to the die, said 100 ladle being adapted to permit its removal from the source of fluid pressure and to permit such material to flow into it, and means for moving said ladle into contact with the die and the source of fluid pressure, 105 whereby when said fluid is admitted under pressure into said ladle, the material within it will be ejected into the die, said ladle being formed of two main separable parts, one of said parts being adapted to have contact with the material to be cast, and the other of said parts being adapted to have 110 contact with the source of fluid pressure.

28. A casting machine having, in combination, a molten metal container, a die having 115 an opening, a source of fluid pressure having an adjustably locatable nozzle, a ladle adapted to receive the metal from the container and to be moved into simultaneous registration with said nozzle and the opening in said die, the adjustability of said nozzle permitting exact registration between said ladle and said source of fluid pressure.

29. A casting machine having in combination, a molten metal container, a die having 120 an opening, a source of fluid pressure also having an opening, a ladle adapted to receive the metal from the container and having corresponding openings to those in said die and said source of fluid pressure, adapted 125 130

to be moved into simultaneous registration with said latter openings, and adjusting means for providing exact registration between said pairs of openings.

30. A casting machine having in combination, a molten metal container, a die having an opening, a ladle, adapted to receive the metal from said container, having a protruding mouth, means for bringing the 10 mouth of said ladle into registration with the opening in said die for the discharge of the metal thereinto, said die opening being of sufficient size to permit the extension of said mouth towards the interior of said 16 die.

31. In a device of the character described, the combination of a molten metal container, a die, a ladle supported over said container on a pivot, said pivot, means for 20 bodily moving said pivot for lowering, raising and laterally moving said ladle in respect to said container and die, whereby the molten metal in the container may be transferred to the die, and means for coun-

terbalancing the weight of said ladle cooperating with said means for moving the ladle.

32. In casting apparatus, the combination of a molten metal container, a source of fluid pressure, a die having an opening, a carrier device having a hollow interior and a mouth 20 communicating therewith, a fluid pressure inlet also communicating therewith, means for moving the carrier adapted to cause the mouth of the carrier to be submerged within the molten metal in the container and to 25 cause the removal of the fluid pressure inlet from the source of fluid pressure at one limit of movement and to cause said mouth to be moved into registration with the die opening and the fluid pressure inlet to be 40 brought into registration with said source of fluid pressure at the other limit of movement and means for effecting both vertical and horizontal adjustment of the registration between said inlet and source of fluid 45 pressure.

MORRIS KATCHER.
